UNITED STATES PATENT OFFICE.

ROBERT F. MORITZ, OF CAMDEN, NEW JERSEY, ASSIGNOR TO SAMUEL M. LANGSTON COMPANY, OF CAMDEN, NEW JERSEY, A CORPORATION OF NEW JERSEY.

CUTTER HEAD.

Application filed October 8, 1921. Serial No. 506,328.

To all whom it may concern:

Be it known that I, ROBERT F. MORITZ, a citizen of the United States, and resident of Camden, in the county of Camden and 5 State of New Jersey, have invented certain new and useful Improvements in Cutter Heads, of which the following is a specification.

This invention is an improvement in cutter heads adapted to be secured to a rotary shaft or other supporting element and rotated in juxtaposition to a cooperating cutter or other element for slitting, trimming, or scoring sheet material. The invention 10 relates particularly to the means employed for securing the cutter in position and permitting of its adjustment lengthwise of the shaft, and includes an expandable and contractible split collar to carry the cutter. 15 In constructions of this type heretofore employed, it has been customary to bore the split ring or collar to an internal diameter slightly larger than the external diameter of the shaft, so that when in non-flexed 20 condition it could be moved freely along the shaft to the desired point and then contracted by bringing together the free ends at the slit to grip the shaft. In such constructions the collar does not flex uniformly 25 during the contraction and thus tends to engage the shaft non-uniformly or at a few spaced points. Furthermore, the collar when in normal or operative position is 30 in distorted condition with the metal under strain. After it has remained clamped 35 in place for a considerable length of time the metal often becomes set and the releasing of the connecting screw at the slit does not result in the return of the collar to ex- 40 panded or non-flexed position. In that case it is a difficult operation to force the collar open or drive it along the shaft in making 45 an adjustment. Furthermore, the non-symmetrical contraction often brings the cutter blade slightly eccentric or sprung it or produces undesirable bending strains in it.

In carrying out my invention I form the collar aperture of substantially the same diameter as the shaft, so that with the parts 50 in normal or unflexed condition, the collar fits the shaft friction tight and uniformly about the entire circumference. The connecting means employed is so designed that it acts to flex the collar by expanding it to

a larger diameter, rather than contracting it. 55 Thus the connecting means may be operated to expand the collar to a larger diameter permitting free longitudinal movement of the collar along the shaft, and then may be operated to relieve the collar of tension and 60 the collar will contract to tightly and uniformly fit the shaft. A further operation of the connecting member serves to tightly clamp the collar in place and prevent any expansion or loosening. Thus the collar 65 when in normal clamped and operating position is not under any material flexing strain, is truly concentric with the shaft, is held by uniform and extensive surface contact with the shaft, and does not remain in a 70 flexed condition for any appreciable time, so that the resilience is not destroyed.

In the accompanying drawings I have 75 illustrated one embodiment of my invention. In these drawings,

Figure 1 is an end view,

Fig. 2 is a transverse section on the line 2—2 of Fig. 1,

Figs. 3 and 4 are sectional details on a 80 larger scale, and

Fig. 5 is a sectional detail similar to Fig. 3, but showing a slight modification.

In my improved construction there is employed a split ring or collar 10 to which the circular cutter blade 11 is detachably secured. At the two free ends 12 and 13 of the split ring there is normally a narrow gap or opening due to the thickness of the saw or other tool, in making the cut. These two ends are secured together by a screw 90 14 having threaded engagement with the end 12 and extending through an aperture in a lug or transverse flange portion 15 of the other end. The aperture is slightly larger than the screw so as to form a clearance. The screw is provided with a head 16 and directly in the rear of this head there is provided a stop or transverse abutment 17 preventing or limiting the endwise movement of the screw in respect to the end 95 13. This abutment may be secured in position after the screw has been put in place, and may be driven into slots to hold by friction, or may be soldered or welded in place. The screw head is so formed that the 100 screw may be rotated, any suitable means being provided for this purpose. Preferably the screw head has a socket 18 into

105

which the end of a suitable key may be extended. If the stop or abutment 17 extend substantially across the entire screw head, then the abutment has an aperture 19 as shown in Fig. 3 and in alignment with the socket 18 so that the key may be inserted through the stop into the socket. In some constructions the stop may be comparatively low, as shown at 17^a in Fig. 5, so that it covers only a portion of the screw head, and in that case it is not necessary to have any opening through it. The cutter is preferably secured to the split ring by screws 20, three being sufficient, and these are so spaced as to interfere to the least possible extent with any expansion or contraction of the split ring. The internal diameter of the split ring is bored substantially the same as the external diameter of the shaft to which the ring is to be applied. Before putting on the shaft, the screw 14 is rotated so that the head is forced against the stop 17 and the resulting reaction acts to separate the ends 12 and 13 and expand the ring. In this expanded condition it may be slipped freely along the shaft to the desired position. By then rotating the screw in the opposite direction the split ring or collar is permitted to return to normal position and to tightly fit the exterior of the shaft. By further turning the screw, the two ends 12 and 13 may be drawn tightly together and the cutter head locked in place.

It will be noted that in my improved construction the split ring when in normal and operative position is not flexed or bent from normal, and snugly and uniformly fits the shaft. The only distortion or bending of the split ring is a temporary one occurring only during the adjustment of the cutter head, instead of a practically continuous one, as in prior constructions. Furthermore, any bending strains or warping of the cutter blade itself occurs only during adjustment, and the cutter blade is not subjected to bending or distorting strains when the collar is tightened and the parts are in position for use.

Although I have illustrated the inner surface or diameter of the ring as one continuous and substantially complete cylindrical surface, it will of course be evident that this is not essential and that the internal surface of the ring which engages with the shaft may be made up of a series of spaced surfaces, all with the same radius and center.

Having thus described my invention, what I claim as new and desire to secure by Letters Patent is:—

1. A cutter head including a split ring having free ends and when in non-flexed position presenting an inner curved surface adapted to snugly fit a supporting shaft, a cutter blade secured to said ring, and a screw

carried by one of said free ends and adapted to spread said ends apart and forcibly expand the ring to facilitate the adjustment of the cutter head lengthwise of the shaft.

2. A cutter head including a split ring having free ends and when in non-flexed position presenting an inner curved surface adapted to snugly fit a supporting shaft, a cutter blade secured to said ring, and a screw carried by one of said free ends and adapted to spread said ends apart and forcibly expand the ring to facilitate the adjustment of the cutter head lengthwise of the shaft, and also adapted to draw said ends together to lock the ring on the shaft.

3. A cutter head including a split ring having free ends and when in non-flexed position presenting an inner cylindrical surface of the same diameter as the external surface of the supporting shaft, a cutter blade secured to said ring and a screw having threaded engagement with one end and having a portion held against endwise movement in respect to the other of said ends, whereby the rotation of the screw in one direction acts to forcibly expand the ring to facilitate the adjustment of the cutter head lengthwise of the shaft.

4. A cutter head including a split ring having free ends, a cutter blade secured to said ring, and a screw having threaded engagement with one of said ends and extending through an aperture in the other of said ends, and having a head larger than said aperture, and said last mentioned end having a stop in the rear of the head whereby said screw when rotated in one direction may apply expanding pressure on said ring.

5. A cutter head including a split ring presenting an internal cylindrical surface of a normal diameter substantially the same as the external diameter of the supporting shaft, and means for expanding said ring to facilitate longitudinal adjustment of the cutter head along the shaft, including a screw having threaded engagement with one portion of said ring and held against lengthwise movement in respect to another portion of said ring.

6. A cutter head including an expansible and contractible split ring which when in normal non-flexed condition presents an internal diameter substantially equal to the external diameter of the supporting shaft, whereby when in normal operative position the metal of the ring is in substantially non-flexed condition, means for expanding the ring to larger diameter by a flexing of the metal thereof to facilitate longitudinal adjustment of the cutter head, and a cutter blade secured to said ring.

Signed at Camden in the county of Camden and State of New Jersey this 27th day of September A. D. 1921.

ROBERT F. MORITZ.
